ANTENNA FOR PRODUCING ELLIPTICALLY POLARIZED WAVES

Henry J. Riblet, Cambridge, Mass., assignor, by
mesne assignments, to the United States of
America as represented by the Secretary of War

Application April 3, 1945, Serial No. 586,416

7 Claims. (Cl. 250—33.63)

1

This invention relates to antennas for radio object-locating systems. The invention is particularly directed to an antenna embodying a wave guide transmission line designed to produce circularly polarized electromagnetic radiation; that is, radiation such that at a given point the electric vector is of constant magnitude and rotates at uniform speed. The invention relates equally to the coaxial conductor and hollow-pipe type wave guide transmission lines.

An antenna having the characteristics for producing a circularly polarized radiation has many useful applications. For example, it may be used as a beacon antenna capable of operating in connection with either vertically or horizontally polarized radio object-locating systems.

The principal object of the present invention is to provide a simple and inexpensive radiating array type antenna comprising a wave guide or coaxial line which, when disposed in its contemplated vertical position, is adapted to radiate circularly polarized electromagnetic waves of energy.

Another object of the invention is to provide a slotted wave guide antenna system which is substantially non-directional in the horizontal plane but which is relatively sharply directional (to a controllable extent, if desired) in the vertical plane, and, moreover, in which the waves are circularly polarized (polarization being defined in the sense used in the radio art rather than in the optical sense, and referring here to the direction of the electric vector rather than that of the magnetic vector).

Other objects and novel features of the invention will become apparent as the present description proceeds.

In the drawings:

Fig. 1 is a partial front elevation view of a wave guide antenna embodying the present invention;

Fig. 2 is a partly broken-away perspective of the same; and

Fig. 3 is a vertical sectional view, partly broken away, of a modification of the antenna shown in Fig. 1.

In general the invention comprises a length of high frequency conductor such as a coaxial line or wave guide adapted for interchange of radiant energy with surrounding space through a system of longitudinally disposed slots and a series of concentric rings of conducting material, spaced a small distance apart and separated by dielectric material such as polystyrene or the like to form circumferentially disposed slots. The longitudinally and circumferentially disposed

2

slots are suitably positioned relative to each other to produce circularly polarized radiation as more clearly disclosed hereinafter.

The wave guide 10 shown in the drawings is of the cylindrical type and it is adapted by reason of its dimensions, in accordance with well known principles, to transmit electric waves in the E_0 or TM_{01} mode of transmission. When operating in this mode, the wall of the wave guide 10 will normally have longitudinal oscillating currents, but no transverse oscillating currents, as contrasted with the H_0 or TE_{01} mode in a rectangular wave guide, where both longitudinal and transverse currents are found.

15 Wave guide 10 is formed of a plurality of aligned hollow and cylindrical sections 11 of metal or other electrically conductive material. Each of sections 11 is axially spaced from its next adjacent section a small distance compared to 20 the length of each section which may be determined in accordance with impedance matching requirements and for purposes defined hereinafter.

25 Disk-like members or rings 12 of dielectric material are mounted coaxially with sections 11. Any usual solid dielectric material, such as polystyrene, may be used for members 12, the coefficient of expansion of the dielectric being preferably comparable to that of the metallic sections 11 for mechanical reasons. The circumferential portion of each disk-like member or ring 12 is located between the ends of adjacent sections 11 and serves to space sections 11. If desired, members 12 when in the shape of a ring may be 30 of substantially the same radial dimensions as the thickness of the wall of sections 11 or as disk shaped members may completely or only partially fill the inside of wave guide 10 as indicated in Figs. 3 and 2, respectively. When it is 35 desired that members 12 serve to fill the inside of wave guide 10 it is preferred that each member 12 be in the form of a solid cylinder having a length of one wavelength, each member 12 abutting its adjacent member at a point along the length of each section 11. If desired, the 40 circumferential portion of members or rings 12 may be provided with annular flanges 14 (Fig. 3) having a suitable axial dimension to fit between adjacent sections 11 and serve to space the same. Circumferential surfaces of rings or members 12 or of flanges 14 between adjacent sections are 45 preferably made flush with the outer surface of guide 10 so that the outer wall of guide 10 presents a smooth cylindrical surface. The distance 50 between corresponding points on an adjacent sec-

tion 11 is approximately equal to the wavelength of the energy inside the conductor or guide 10. Also, the distance between corresponding points on adjacent portions of flanges 14 is equal to a wavelength. Radiation of energy occurs from the several circumferential regions or slots, formed between conductor sections 11 by the dielectric member or ring 12, in directions normal to the axis of guide 10. Because of the above-mentioned spacing such radiation will be in phase as is well known in the art. With the antenna, this is the wave guide 10, disposed in a vertical position, the wave energy radiated from the circumferential slots will normally have a vertically polarized characteristic.

Each of sections 11 is provided with a series of substantially equally spaced parallel slots 15 adapted to radiate waves of energy from wave guide 10. In order to obtain the desired circularly polarized radiation of radiated energy waves, it is necessary that slots 15 be so positioned that the waves radiated by slots 15 will be in the proper phase relation with the energy waves emitted through circumferential dielectric portions 13. The slots 15 are consequently longitudinally oriented in each of sections 11 so that each slot is parallel to the axis of the wave guide 10 and perpendicular to the planes of the dielectric members or rings 12. Slots 15 are of equal dimensions and are arranged so that each slot 15 is equally distant from both ends of its corresponding section 11, thereby forming a ring of spaced parallel slots about the circumference of each section 11. The spacing between successive rings of slots measured longitudinally of the wave guide 10 between central planes is designed to provide the desired phase difference. Accordingly, such spacing should be equal to the wavelength of oscillations in the wave guide 10.

In order that the radiation may pass through the slots in appreciable amounts, the electric field of the waves in the wave guide is distorted in the neighborhood of the centers of the slots by means of radially disposed projections or probes of metal or other electrically conductive material such as the screws 16, extending radially into the wave guide 10, as shown in Fig. 3.

The direction and intensity of the transverse electric field across the slot is determined by the length of screws 16.

For longitudinal spacings between centers of the order of one wavelength the screws of successive slot rings will be similarly placed (non-reversed array) instead of oppositely placed (reversed array).

The phase of radiation from the circumferential slots (the circumferential space between adjacent sections 11 filled by the dielectric member or ring 12) is that of the current across these circumferential slots. The phase of radiation from the center points of the longitudinal slots 15 such as at A is that of the resultant voltage vector at such points A. Since the phase angles of the voltage and current vectors depend on the propagation constant of the conductor line and on the reflection factor, the desired 90° time phase difference between voltage vector and current vector at the circumferential and longitudinal slots respectively may be obtained by proper adjustments of the depth of projection of the screw probes 16 into the wave guide 10 and by providing an adjustable terminating plunger 17 (Fig. 1) at one end of the line as is well known in the art. The effect of all the circumferential slots will be additive since they

are spaced one wavelength apart and the radiation therefrom is in time phase. For the same reason, radiation emanating from the longitudinal slots 15 is in time phase.

However, as a 90° time phase relationship exists between radiations from the longitudinal and circumferential slots, the resultant voltage vector of radiation, considered at a very large distance from the wave guide 10 compared to the wavelength in the guide, will be circularly polarized, due to the fact that space quadrature also exists. The magnitude of the voltage vectors may be made equal by proper adjustment of the depth of screws 16 and the width or axial dimension of the circumferential slots or regions between the adjacent ends of sections 11.

From the foregoing description it will be clear that fundamentally there has been disclosed an antenna structure for radiating circularly polarized waves or more generally elliptically polarized waves comprising a metallic wave guide having means for radiating or receiving radio frequency energy which is comprised of at least one slot shaped aperture in the wall of the guide which is oriented for a maximum radiation of energy from the guide and at least one slot shaped aperture in the wall of the guide which is oriented perpendicular to the first aperture normally to radiate a minimum of energy from the guide and means extending and adjustable into the guide are provided for coupling energy therefrom to the second aperture in order to provide radiation therefrom having a time phase displacement relative to the radiation from the first aperture of ninety electrical degrees.

While the present description has been principally directed to a wave guide of circular cross-section, it will be understood that the invention is not limited to this structure. For example, by suitably arranging the longitudinal and circumferential slots, circularly polarized radiation may be produced with wave guide or coaxial conductor of elliptical or rectangular cross-section.

It will also be understood various other modifications and improvements may be made within the scope of the present invention and therefore it is not desired that the invention be limited to the precise details set forth herein.

What is claimed is:

1. An antenna array comprising a transmission line having a tubular wave-guiding wall within which high frequency electromagnetic waves are propagated, said wall comprising a plurality of axially aligned individual metallic sections, said sections being spaced a predetermined distance thereby forming circumferentially disposed slots through which energy is adapted to radiate into free space, dielectric members disposed within said sections and between the spaced ends of adjacent sections thus serving to space said sections and to fill said circumferential slots, the axial distance between corresponding points on adjacent sections and on adjacent dielectric members being substantially equal to a wavelength of the guided wave, each of said metallic sections having a plurality of parallel longitudinal slots arranged with the long dimension of each slot parallel to the axis of said line, said slots being substantially equally spaced about the circumference of each section so that the ends of each of said longitudinal slots are equidistant from the adjacent ends of each section, and at least one metallic projection associated with each of said longitudinal slots mounted on said wall near the middle of said longitudinal

slots and extending into said transmission line, said projection being effective to cause radiation through said longitudinal slots in suitable amplitude and phase relationship with the radiation through said circumferential slots to produce circularly polarized radiation in a beam which is substantially non-directional in a horizontal plane and which is relatively sharply directional in a vertical plane.

2. An antenna array comprising a hollow wave guide for high frequency electromagnetic waves adapted for interchange of energy with surrounding space including a tubular metallic wave-guiding wall of circular cross-section adapted to transmit oscillations at a desired frequency in the $TM_{0,1}$ mode, said wall comprising a plurality of aligned individual conductive sections, said sections being spaced a predetermined distance, the spacing between adjacent sections forming circumferential slots in said wall, a plurality of dielectric cylindrical members, each of said members being disposed coaxially within said sections, the circumferential portion of each member disposed in said circumferential slots being substantially flush with the outside surface of said sections, the axial distance between corresponding points on adjacent sections and on adjacent dielectric members being substantially equal to a wavelength of the guided wave, each conductive section having a series of slots circumferentially spaced around the section and longitudinally oriented with the long dimension of the slots parallel to the axis of the guide and with the ends of each longitudinal slot being equidistant from the adjacent ends of each section, and at least one metallic adjustable projection mounted on said wall near the middle of each longitudinal slot and extending into said wave guide, said projection being adapted to distort longitudinal currents in said tubular wall when said wave guide is excited and thereby to provide for flow of wave energy through said longitudinal slots, said projections being so disposed with respect to said longitudinal and circumferential slots to provide 90° time phase difference between the energy at the circumferential and longitudinal slots whereby circularly polarized radiation from said slots is produced.

3. An antenna array including a hollow cylindrical wave guide within which high frequency electromagnetic waves are propagated, said wave guide comprising a plurality of spaced aligned conductive sections, the space between said sections affording circumferential slots around the guide adapted to radiate energy to surrounding space, a dielectric member disposed in each of said circumferential slots, each of said conductive sections having a plurality of longitudinal slots therein oriented with the long dimension of the slots parallel to the cylindrical axis, each of said longitudinal slots being equidistant from the adjacent end of each section, at least one metallic projection mounted on said wave guide near the midpoint of each longitudinal slot and extending into said wave guide, said projections being effective to cause radiation from said longitudinal slots, the axial distance between corresponding points on adjacent sections being substantially equal to a wavelength of the guided waves whereby a 90° time phase relationship and space quadrature exists between radiations from said longitudinal and circumferential slots whereby the resultant voltage vector rotates to produce circularly polarized radiation.

4. An antenna array including a hollow cylind-

rical wave guide within which high frequency waves of electromagnetic energy are propagated, said wave guide comprising a plurality of spaced aligned individual sections of electrically conductive material, the spaces between said sections affording slot shaped circumferential regions around the guide for energy to radiate therethrough, each of said sections having radiating slot shaped means disposed with the long dimension perpendicular to the planes of said circumferential slot shaped regions, the spacing of the centers of said radiating means on adjacent sections being a wavelength of the energy in said wave guide, and means adjustably extendable into said guide adjacent each one of said radiating means to provide a 90° time phase relationship between radiations from said circumferential regions and said radiating means to effect circularly polarized radiation from said wave guide.

5. An antenna array including a tubular transmission line for propagation of high frequency waves of electromagnetic energy, said tubular line being provided with two series of slots therein, the longitudinal axes of the slots of one of said series lying in planes perpendicular to the axis of said tubular line, the longitudinal axis of the slots of the other of said series lying in planes parallel to the axis of said tubular line, and a metallic projection into said tubular line adjacent each of said slots of said other series for producing radiation therefrom with a phase shift of 90° with respect to the radiation from the slots of said one series, the centers of the slots of one of said series being axially spaced a half wavelength of the energy in said line from the centers of the slots of the other of said series to produce elliptically polarized radiation from said line.

6. An antenna structure for radiating elliptically polarized waves comprising a metallic wave guide having means for radiating energy applied thereto, said guide comprising at least one slot-shaped aperture oriented with the long dimension perpendicular to the longitudinal axis of said guide and approximately symmetrically disposed about a current maximum point, at least one slot-shaped aperture oriented with the long dimension parallel to the longitudinal axis of said guide and approximately symmetrically disposed about a current minimum point, the respective centers of said first-mentioned and said second-mentioned apertures being spaced along the length of said guide approximately a distance of one-half wavelength at the operating frequency of said energy, and adjustable means extending into said guide adjacent to said second-mentioned aperture for coupling energy from said guide to said second-mentioned aperture and for varying the propagation constant of said guide, whereby the propagation constant of said guide may be adjusted to a value which makes the distance between said centers of said apertures exactly one-half wavelength at the operating frequency of said energy.

7. An antenna structure for radiating elliptically polarized waves comprising a metallic wave guide having means for radiating energy applied thereto, said guide comprising at least one slot-shaped aperture oriented with the long dimension perpendicular to the longitudinal axis of said guide, at least one slot-shaped aperture oriented with the long dimension parallel to the longitudinal axis of said guide, the respective centers of said first-mentioned and said second-

mentioned apertures being spaced along the length of said guide approximately a distance of one-half wavelength at the operating frequency of said energy, and adjustable means extending into said guide adjacent to said second-mentioned aperture for coupling energy from said guide to said second-mentioned aperture and for varying the propagation constant of said guide, whereby the propagation constant of said guide may be adjusted to a value which makes the distance between said centers of said apertures exactly one-half wavelength at the operating frequency of said energy.
